United States Patent Office.

MARTIN LANDENBERGER, OF PHILADELPHIA, PENNSYLVANIA.

Design No. 4,164, dated June 21, 1870.

DESIGN FOR "BASCHLIKS."

The Schedule referred to in these Letters Patent and making part of the same.

all whom it may concern:

Be it known that I, MARTIN LANDENBERGER, of Philadelphia, in the county of Philadelphia and in the State of Pennsylvania, have invented a certain new and useful Design for Ladies' Knitted Wearing-Apparel; I do hereby declare that the following is a full, clear, and exact description thereof, reference being had to the accompanying drawing and to the letters of reference marked thereon making a part of this specification. The nature of my design is fully represented in the accompanying drawing, and consists in the peculiar shape of the article, irrespective of color or stitch. This article, made as shown, may be used as a hood and nubia combined, or as a breakfast-shawl, for throwing over the shoulders, &c.

Claim.

I claim as my invention—

The design for ladies' "baschlik," as shown and described.

In testimony that I claim the foregoing, I have hereunto set my hand this 21st day of May, 1870.

MARTIN LANDENBERGER.
